UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

Application filed April 13, 1922. Serial No. 552,225.

My invention relates to electric switches, and particularly to a switch mechanism of the quick make and break type adapted to control lighting circuits and the like. The object of my invention is to provide a mechanism of this sort in which the switch opening movement of the commutator is positively initiated while still maintaining the advantage of spring action for effecting quick throw of the commutator to break the circuit.

In the accompanying drawings—

Fig. 1 is a vertical section through an electric lamp socket in which a switch embodying my invention is illustrated;

Fig. 2 is a plan view thereof with the upper insulating button of the socket body removed;

Fig. 3 is a section on the line 3—3, Fig. 2; and

Figs. 4 and 5 are similar views showing the switch mechanism at different stages of operation.

In its main features, the present switch resembles that shown in the patent to De Reamer No. 1,059,846, and for convenience is illustrated in an electric lamp socket. As in that construction, the socket body comprises a pair of insulating buttons 6 and 7, suitably recessed on their adjacent faces to form a switch chamber. On the button 7 is mounted the usual screw shell contact 8, which is held in position by the flange 9 of the wire terminal bracket 10, secured on the button 7 by screw bolts (not shown) passing through holes 11 and 12 in the buttons 6 and 7. The center contact 13 is secured by a rivet 14 to the base of the switch contact 15 which cooperates with a second contact 16 secured beneath the wire terminal bracket 17. The commutator or switch bar 18 is of U-shape and bridges the contacts 15 and 16 in circuit-closing position, the switch mechanism serving to throw it to the position indicated in dotted lines in Fig. 3 to open the circuit. The commutator is pivoted at 19 on the frame member 20 carried by the button 7 and pierced to afford bearings for the switch operating spindle 21, actuated by the thumb piece 22 fast thereon.

At the inner end of the spindle 21 is a crank arm 23 having an offset stud 24, against which the head 25 of the pin 26 is seated by the switch-operating coil spring 27. The opposite end of the latter bears

against the free end of the commutator 18 and surrounds an inwardly struck boss 28 thereon.

The axis 19 on which the commutator rocks, intersects that of the spindle 21. Consequently, when the spindle is rotated, its crank arm 23 shifts the crank end of the spring 27 across the axis of oscillation of the commutator. The biasing effort of the spring, which bears at its opposite end 65 against the bridge end of the commutator, is thus exerted in the opposite direction, and the latter is thrown with snap action from circuit closing to open circuit position, or vice versa, on the rotation of the spindle in 70 either direction.

In the construction shown in the De Reamer patent above mentioned, the pin 26 is carried freely through the bridge end of the commutator and serves no other function than that of a guide for the switch actuating spring 27. The biasing action of the spring thus constitutes the sole means for oscillating the commutator to make or break the circuit through the switch. It 80 not infrequently happens, however, that the surfaces of the contacts 15 and 16, or the cooperating surface of the commutator itself, become oxidized. Under such conditions, or even when the contacts 15 and 16 are set too 85 close together during assembly, the friction between the engaging surfaces may be sufficient to overcome the biasing effort of the switch spring, and consequently the rotation of the switch spindle 21 fails to throw 90 the switch to open circuit position. I have remedied this defect in the mechanism by so constructing the parts that the movement of the commutator is positively initiated, while the biasing action of the spring is still maintained to effect the snap action of the mechanism. 95

For this purpose I utilize the pin 26 as a thrust member which positively engages the commutator on the rotation of the spindle, 100 and forces it from its extreme position at one side or the other of its axis of oscillation. It is of course obvious that the crank arm stud 24 rotates in a plane, and that the bridge 18 of the commutator rocks 105 on an arc, the prolongation of which intersects the plane of rotation of the stud 24. Furthermore, when the parts are in a position of rest (Fig. 3) the stud 24 and the commutator bridge 18 lie on opposite sides 110

of the axis of oscillation 19 of the latter, and are spaced as far apart (under the pressure of the spring 27) as the construction and arrangement of the switch mechanism permits. It will be noted that in this position the free end of the thrust pin 26 is spaced from the boss 28 of the bridge 18.

As the spindle 18 is rotated, however, the crank arm stud moves downward in its plane of rotation, and eventually across the axis of oscillation of the commutator to a point at which its distance from the commutator bridge is materially less than that at which these parts are spaced in the position of rest. During this downward movement of the stud, the free end of the pin 26 gradually approaches the boss 28 on the commutator bridge, and approximately as the crank arm crosses the axis of oscillation 19 the pin end engages the boss 28 (Fig. 4). On further rotation of the spindle, in the same direction, the pin 26, now acting as a rigid strut between the crank arm and the bridge 18, forces the latter to swing outward on its axis away from the plane of rotation of the crank arm, and thus positively frees it from engagement between the contacts 15 and 16 (Fig. 5). Inasmuch as the stress on the spring 27 has been simultaneously increased, and its biasing effort is in opposite direction, owing to the fact that its abutment (the crank arm) has been shifted across the axis of oscillation of the commutator, the latter is now thrown with snap action to open circuit position (Fig. 3, dotted lines).

The particular construction of the pin and of its bearing abutment upon the commutator may be variously modified, as well as the proportions between these parts and the crank arm 23. The mechanism is not limited in its utility to an electric socket switch, and may be applied to other devices as well.

The angular throw of the commutator may be limited in many ways. I have shown its legs extended beyond the pivot axis 19 to form stop wings 29, which work between the base of the frame 20 and stop lugs 30 offset from the top of one of the frame uprights.

Various modifications in detail and ar-

rangement of the parts will readily occur to those skilled in the art, which do not depart from what I claim as my invention.

I claim—

1. A mechanical movement for electric switches and the like, comprising a member rotating substantially in a plane, a pivoted member oscillating across the axis of rotation of said member and on an arc intersecting said plane, and a bodily movable thrust member bearing at one end against said rotating member and normally out of but moving into positive displacing engagement with said pivoted member when said rotating and pivoted members are brought to the same side of the axis of the rotary member by the relative displacement of said rotary member with respect to said pivoted member.

2. A mechanical movement for electric switches and the like, comprising a member rotating substantially in a plane, a pivoted member oscillating across the axis of rotation of said member and on an arc intersecting said plane, and a thrust member bearing at one end against said rotating member and normally spaced from said pivoted member, but moving into operative engagement with the latter when said rotating and pivoted members are brought to the same side of the axis of the rotary member by the relative displacement of said rotating member with respect to said pivoted member, together with a spring interposed between said rotating and oscillating members, and stressed by the rotation of the former.

3. In an electric switch, a rotary switch spindle, a crank operated thereby and rotating substantially in a plane, a commutator pivoted to oscillate across the axis of said spindle, a spring interposed between said crank arm and commutator for imparting a quick throw to the latter, and a thrust rod having a thrust engagement with said commutator on the rotation of the crank to the same side of its axis of rotation as that on which the commutator lies.

In testimony whereof I have signed my name to this specification.

GEORGE B. THOMAS.
